Parma, Idaho

Application July 22, 1936, Serial No. 92,028

4 Claims. (Cl. 261—80)

This invention relates to an improved air conditioning apparatus of the type disclosed in our co-pending application Ser. No. 50,438 filed November 18, 1935.

5 The primary object of the present invention is to provide an improved air conditioning apparatus of the above type which will be most satisfactory and efficient in operation.

More particularly, the present invention contemplates the provision of an air conditioning apparatus of the above type including a bottom water pan, a horizontal open ended casing mounted on said water pan and having an opening for the discharge of humidified air in the lower intermediate portion thereof, a motor-operated centrifugal fan blower arranged within said open ended casing and having side air inlets coaxial with the open ends of said casing and a tangential peripheral outlet coincident with the outlet or discharge opening of the open ended casing, and means for elevating water from the bottom water pan into the open ended casing in the path of air flowing in one end of said open ended casing to the adjacent side inlet of the fan blower.

25 A more particular object of the present invention is to provide an air conditioning device of the above character wherein the impeller of the fan blower is rotated in a direction to throw the humidified air and water downwardly at and adjacent the blower outlet so as to minimize the discharge of excess moisture from the blower and the open ended casing, the casing of the fan blower being provided with bottom drain openings to permit the drainage of such excess moisture therefrom back into the bottom water pan. 35 This involves rotation of the impeller of the fan blower in a direction reverse to the natural or normal rotation of such impeller in the ordinary use of fan blowers, and we have found that the same produces a marked increased efficiency in the operation of the apparatus without materially lessening the volume of air delivered by the blower.

40 A further object of the present invention is to provide an air conditioning apparatus of the above character wherein the open ended casing is provided with a discharge conduit for the humidified air which extends from the discharge opening of said open ended casing partially around the latter and gradually increases in width and decreases in depth toward its discharge end to provide for uniform volumetric capacity throughout its length and to cause the humidified air to be spread over a relatively wide area as it is discharged from the discharge conduit into

the room or other enclosure in which the apparatus is used.

With the above general objects in view, and others that will become apparent as the nature of the invention is better understood, the present invention consists in the novel form, combination and arrangement of parts hereinafter more fully described, shown in the accompanying drawings and claimed.

In the drawings:

Figure 1 is an end elevational view of an air conditioning apparatus embodying the present invention.

Figure 2 is a rear elevational view thereof.

Figure 3 is a transverse section on line 3—3 of Figure 2; and

Figure 4 is a longitudinal section on line 4—4 of Figure 1.

Referring in detail to the drawings, the present invention includes a shallow elongated water pan 20 or receptacle 5 having a somewhat restricted top opening and provided along the sides and ends of this opening with a depending annular flange 6. Suitably mounted upon the bottom water pan 5 is a horizontal open ended casing 7 having a 25 bottom longitudinal opening registered with the top opening of water pan 5 and preferably being of cylindrical form. This casing 7 is provided along the sides and ends of its bottom opening with a flange 8 projecting downwardly and fitting into the annular flange 6 of the water pan 5, so that any excess moisture which finds its way onto the walls of casing 7 will ultimately drain back into the water pan 5 for re-use. The 30 ends of the casing 7 are open for the intake of air to be humidified, and each end is provided with a foraminous covering preferably consisting of a removable screen 9 provided on its inner side with a layer of metal wool 11 for extracting dirt and foreign matter from the air as it enters the casing 7.

Seated on the angular flange 6 of the water pan 5 is an elongated rectangular open frame 12, preferably constructed of angle iron. This frame forms a support upon which is secured the base 45 14 of an electric motor 15 positioned near the axis of the casing 7 and near one end of the latter.

The casing 7 is provided in its rear lower portion with an opening 16 of rectangular and nearly square form, and outwardly through which the 50 humidified air may be discharged from said casing 7, as will presently become apparent. Extending upwardly and forwardly partially around the casing 7 from the outlet opening 16 is a discharge conduit 17 for the humidified air, which 55

conduit 17' gradually increases in width and decreases in depth toward the upper forward discharge end thereof, so as to maintain a uniform volumetric capacity and at the same time cause 5 the discharge of humidified air from the outlet end thereof so that it will spread over a comparatively large area within the room in which the apparatus is used.

Suitably supported and arranged within the 10 open ended casing 7 intermediate the ends of the latter is a centrifugal fan blower including the usual volute casing 17 and rotary bladed impeller 18 whose shaft 19 is suitably coupled at 15 20 to the armature shaft of motor 15. The blower casing 17 has air intake openings 21 in the opposite sides thereof coaxial with the open ends of casing 7, and is provided with a tangential peripheral air outlet 22 which registers with the air outlet opening 16 of casing 7. As viewed in 20 Figure 3, the impeller 18 is usually rotated in a clockwise direction, but in accordance with the present invention such impeller is reversely rotated or rotated in a counter-clockwise direction as indicated by the arrow *a*, for a purpose which 25 will presently be made apparent. The casing 17 of the fan blower is further provided with a plurality of drain openings 22' in the bottom portion thereof, so as to permit drainage of excess moisture from the casing 17 through the bottom 30 opening of casing 7 back into the water pan 5 for re-use.

Secured on the armature shaft of motor 15 is a pulley 24 around which passes an endless belt 25, and this belt extends downwardly through 35 the bottom opening of casing 7 and the top opening of pan 5 where it passes around another idler pulley 26 mounted within and near the bottom of water pan 5. The idler pulley 26 is preferably journaled on the lower end of an arm 27 depending from the frame 12. It will thus be seen that the belt 25 is arranged in a vertical plane between one end of casing 7 and the adjacent side air inlet 21 of the fan blower. A suitable shield 28 is placed over the inner end 40 of motor 15 between the latter and the pulley 24, so as to protect said motor 15 from any water which may be splashed or thrown outwardly from the belt 25 as it is driven by said motor 15.

In operation, the motor 15 is suitably rendered 50 operative so as to rotatably drive the impeller 18 of the fan blower and to cause travel of the belt 25. The travelling belt 25 moves through the water in the bottom pan 5 so as to take up some of such water and elevate it into the upper open 55 ended casing 7 in the path of air drawn into the adjacent open end of casing 7 and into the side air inlet 21 of the blower adjacent such belt 25. As the impeller 18 revolves rapidly, it causes a rapid flow of air into casing 7 through the 60 open ends of the latter. When this takes place, the water from the belt 25 is drawn into the casing 17 of the fan blower where it mixes with the air and is thrown outward under centrifugal force against the wall of said blower casing 17, being 65 ultimately thrown downwardly against said casing 17 and the intake end of discharge conduit 17' at the bottom of the same as indicated by the arrows *b*. This causes the elimination of any spray being discharged into and through the conduit 17', the excess moisture being separated from 70 the humidified air and draining from the blower casing 17 through opening 22 back into the water pan 5 for re-use. In practice, an apparatus constructed in accordance with the above has been 75 found to operate with great efficiency, and to lend

itself to a variety of embodiments and uses. Moreover, the apparatus is extremely compact and durable as well as relatively quiet in operation and inexpensive to produce and operate. It will be apparent that minor changes may be made in certain structural details illustrated and described, without departing from the spirit and scope of the invention as claimed.

What we claim as new is:

1. An air conditioning apparatus comprising a 1 water pan, a horizontal open ended casing mounted upon said water pan and communicating with the latter, said open ended casing having a discharge opening for humidified air in the lower intermediate portion thereof, a motor-operated 1 centrifugal fan blower mounted and arranged within said open ended casing intermediate the ends of the latter and including a volute casing and a rotary impeller, said volute casing having 2 side air inlet openings coaxial with the open ends of said horizontal open ended casing, said volute casing further having a lower tangential peripheral air outlet registered with the air outlet of said horizontal open ended casing, and a motor-driven belt for elevating water from said water pan into the horizontal open ended casing and in the path of air flowing to a side inlet of said blower through one open end of said open ended casing.

2. An air conditioning apparatus comprising a 3 water pan, a horizontal open ended casing mounted upon said water pan and communicating with the latter, said open ended casing having a discharge opening for humidified air in the lower intermediate portion thereof, a motor-operated 3 centrifugal fan blower mounted and arranged within said open ended casing intermediate the ends of the latter and including a volute casing and a rotary impeller, said volute casing having 4 side air inlet openings coaxial with the open ends of said horizontal open ended casing, said volute casing further having a lower tangential peripheral air outlet registered with the air outlet of said horizontal open ended casing, and a motor-driven belt for elevating water from said water pan into the horizontal open ended casing and in the path of air flowing to a side inlet of said blower through one open end of said open ended casing, the driving motor of said fan blower 41 rotating said impeller in a direction to throw 42 the humidified air downwardly onto the bottom 43 of the blower outlet, said blower casing having 44 bottom drain openings to permit excess moisture 45 to pass therefrom downwardly and back into said 46 water pan.

3. An air conditioning apparatus comprising a 50 water pan, a horizontal open ended casing mounted upon said water pan and communicating with the latter, said open ended casing having a discharge opening for humidified air in the lower 60 intermediate portion thereof, a motor-operated 60 centrifugal fan blower mounted and arranged within said open ended casing intermediate the ends of the latter and including a volute casing and a rotary impeller, said volute casing having 65 side air inlet openings coaxial with the open ends of said horizontal open ended casing, said volute casing further having a lower tangential peripheral air outlet registered with the air outlet of said horizontal open ended casing, a motor-driven belt for elevating water from said water pan into the horizontal open ended casing and in the path of air flowing to a side inlet of said blower through one open end of said open ended 70 casing, the driving motor of said fan blower 75

rotating said impeller in a direction to throw the humidified air downwardly onto the bottom of the blower outlet, said blower casing having bottom drain openings to permit excess moisture to 5 pass therefrom downwardly and back into said water pan, and a discharge conduit for humidified air extending from the air outlet of said horizontal open ended casing upwardly and forwardly partially about said open ended casing.

10 4. An air conditioning apparatus comprising a water pan, a horizontal open ended casing mounted upon said water pan and communicating with the latter, said open ended casing having a discharge opening for humidified air in the 15 lower intermediate portion thereof, a motor-operated centrifugal fan blower mounted and arranged within said open ended casing intermediate the ends of the latter and including a volute casing and a rotary impeller, said volute 20 casing having side air inlet openings coaxial with the open ends of said horizontal open ended casing, said volute casing further having a lower

tangential peripheral air outlet registered with the air outlet of said horizontal open ended casing, a motor-driven belt for elevating water from said water pan into the horizontal open ended casing and in the path of air flowing to a side inlet of said blower through one open end of said open ended casing, the driving motor of said fan blower rotating said impeller in a direction to throw the humidified air downwardly onto the bottom of the blower outlet, said blower casing having bottom drain openings to permit excess moisture to pass therefrom downwardly and back into said water pan, and a discharge conduit for humidified air extending from the air outlet of said horizontal open ended casing upwardly and forwardly partially about said open ended casing, said discharge conduit gradually increasing in width and decreasing in depth toward the discharge ends thereof.
